UNITED STATES PATENT OFFICE.

LETITIA E. STEWART, OF PHILADELPHIA, PENNSYLVANIA, ASSIGNOR OF ONE-HALF TO HENRY SCHMIDT, OF PHILADELPHIA, PENNSYLVANIA.

APPARATUS FOR PACKING HATS FOR STORAGE AND SHIPMENT.

SPECIFICATION forming part of Letters Patent No. 762,259, dated June 7, 1904.

Application filed August 16, 1902. Serial No. 119,925. (No model.)

To all whom it may concern:

Be it known that I, LETITIA E. STEWART, a citizen of the United States, residing at Philadelphia, in the county of Philadelphia and 5 State of Pennsylvania, have invented new and useful Improvements in Apparatus for Packing Hats for Storage and Shipment, of which the following is a specification.

My invention relates to a certain new and 10 useful apparatus for packing hats for storage and shipment, and has for its object to pack the hats in such manner as that the maximum number of hats can be placed in a box or crate of a given size without being in contact one 15 with the other and without being caused to lose their shape, while at the same time all of the hats will be securely held in position.

While my invention may be used generally 20 in the shipment of hats from the manufacturer to the jobber, it is intended that it shall find its widest application in the packing for storage and shipment of what are known as "campaign-hats," used by the soldiers in our Army. These hats are of soft felt, with a broad brim 25 and rather high crown, and many thousands of them are kept on hand in storage-houses of the Government ready for shipment to the soldiers here and in the Philippine Islands. Owing to the fact that these hats often remain 30 in the storehouses for many months before shipment, if they are packed so that one hat is in engagement with the other or if the hats be crushed in packing it is found that they will be discolored in the first case or permanently 35 deprived of their shape in the second case. It is required, therefore, by the Quartermaster's Department that these hats be packed in such manner that they may remain in storage an indefinite length of time without losing 40 their shape or becoming discolored. In order to meet this requirement, the manufacturer packs four hats in a bandbox, and a given number of these bandboxes containing hats are placed in a wooden box and so shipped to the 45 place of storage. The boxes now employed are of a size to hold forty-eight hats in twelve bandboxes.

According to my invention the hats can be packed in a manner to meet all of the above

requirements, and a box of approximately the 50 same size as but somewhat smaller than that now employed will hold one hundred and eight hats when so packed. It will thus be seen that by the use of my invention a great saving in storage-space and in freight can be effected. 55

Having thus set forth the nature and objects of my invention, I will now describe the same in detail, referring to the accompanying drawings, in which—

Figure 1 is a sectional elevation, on an enlarged scale, of a portion of a box having hats packed therein according to my invention. Fig. 2 is a plan view of the box, showing the lowermost partition, having a series of collars therein for receiving the crowns of the hats. 65 Fig. 3 is a view in sectional elevation of the same. Fig. 4 is a plan view showing five hats placed in the collars of said lowermost partition. Fig. 5 is a sectional elevation of the same. Fig. 6 is a plan view showing a 70 layer of paper or other material provided with nine holes adapted to align with the openings in the collars of the partition and placed over the five hats shown in Fig. 4. Fig. 7 is a similar view showing four hats placed in 75 the collars left vacant in Fig. 5, their brims resting on the paper or other layer shown in Fig. 6. Fig. 8 is also a plan view, similar to Fig. 6, showing the layer of paper or other material placed over the four hats of Fig. 7. 80 Fig. 9 is a plan view of the second partition, showing five hats placed in the collars thereof in the same manner as shown by Fig. 4; and Fig. 10 is a sectional elevation of the 85 same.

Referring now to the drawings, 1 indicates a wooden box rectangular in shape and of any desired size, in which the hats are to be packed. Said box, however, may, if preferred, have a contour other than rectangular. On the bottom of this box is supported the lowermost partition, which consists of a sheet of cardboard 2, conforming to the shape and of a size to fit snugly the interior of the box 1 and provided with nine holes 3, in each one of which 90 is fitted a strip of pasteboard, curved upon itself to form a substantially circular collar 4. These collars may be glued or otherwise se-

cured in position, if desired; but ordinarily they are made to fit in the holes 3 so tightly that no further securing means will be found necessary. The holes 3, and consequently the 5 collars 4, are arranged in three rows of three each, as shown by Fig. 2, and the collars at the corners and the center of the partition project a given distance—say one-half inch—above the partition 2, while the remaining 10 four collars (indicated by the numeral 5 in Fig. 4) project a slightly-greater distance above the partition. All of these collars project an equal distance below the partition, and this distance is such that when the hats are inserted 15 in the collars their crowns will be held above the bottom of the box, as shown in Fig. 1. The first partition being placed in the bottom of the box, as shown by Fig. 3, five hats 20 6 are placed in the collars 4, crown downward, one hat being placed in each corner-collar and one in the center, as shown by Fig. 4. These collars project a sufficient distance above the partition 2 to allow the edges of 25 the rims of the hats just to touch or rest on said partition, and thus the natural shape of the rim is preserved. I next place over these hats a sheet of thick Manila paper 7 of the same size and shape as the partition 2 and having a like number of holes correspondingly arranged, and I then place four hats in 30 the openings or collars 5, as shown by Fig. 7. The layer of paper 7 is thus interposed between the five hats shown in Fig. 4 and the four hats shown in Fig. 7, and thus all the 35 hats in the layer are kept out of contact, as the holes 3 are far enough apart to prevent the rims of the hats engaging edgewise. The increase in height of the collars 5, before referred to, is to allow for the thickness of the 40 brims of the first five hats resting on the edges of the other collars, so that the brims of the four hats will be supported in their natural positions. A second sheet of paper 45 8, similar to that shown by Fig. 6, is then placed over the four hats of Fig. 7, as shown by Fig. 8. A second partition 9, having collars 10 arranged therein in the same manner as the partition 2, is now placed on the layer of paper 8, and five hats are placed therein at 50 the corners and center, as shown by Fig. 9. The collars 10, however, are of much less depth than the collars 4. In other words, 55 their height is such that the crowns of the hats placed therein will enter or "nest" within the hats of the first layer; but they will not come in contact with the leather hatbands on the inside of the latter, this position of the hats being clearly shown by Fig. 10. In practice the height of the collars 10 is two and 60 one-quarter inches, except that the four side collars 11 are slightly higher for reasons previously explained with reference to the collars 5. The purpose of the second sheet of paper 8 is to prevent the lower edges of the 65 collars 10 from resting directly on the brims

of the four hats of the first layer, which might cause discoloration of said brims or injury by abrasion. The method of filling the remainder of the box with hats is a repetition of what has just been described—that is to say, 70 a sheet of paper 7 or 8 is placed on the five hats shown in Fig. 9, four hats are placed in the collars 11, a second sheet of paper is placed over the four hats, and another partition similar to 9 is then inserted, and so on 75 until the box is filled. In practice there will be twelve layers of hats, with nine hats in each layer, or a total of one hundred and eight hats. In each case the second layer of paper 8 may be pasted or glued to the bottom edges 80 of the collars 10 to save additional handling.

While in storage the box 1 is laid on its side, so that each hat will rest independently upon the collar surrounding it. According to the present method of packing hats in bandboxes, if the box containing the bandboxes be laid on its side the hats will rest on the soft rims and be caused to lose their shape. Also the lids of these bandboxes are liable to come off, allowing the hats to fall into positions which will ultimately cause them to 90 lose their shape.

While I have described the partitions and collars as being made of pasteboard and the protecting layers of paper, it will be obvious 95 that other materials may be substituted for these but those named will answer every purpose and are presumably the most economical.

Having thus fully described my invention, what I claim as new is—

1. A crate of the character specified, comprising a receptacle, a plurality of partitions disposed therein and having hat-receiving collars of different heights projecting beyond both sides thereof, and interposed sheets of flexible material having openings alining with the collars.

2. Apparatus for packing hats comprising a series of superposed partitions each of which is provided with a number of collars projecting above and below the same, certain of said collars projecting a greater distance above the partition than others, and the collars in each partition serving as the support therefor.

3. Apparatus for packing hats comprising a series of superposed partitions each of which is provided with a number of collars projecting above and below the same, certain of said collars projecting a greater distance above the partition than others, and the collars in each partition serving as the support therefor, and flexible brim-protecting means.

4. A crate for packing hats comprising a receptacle, a partition having a number of collars secured therein inserted in the receptacle, and adapted to receive a number of hats having their crowns inserted within certain of said collars, a sheet of material having holes alining with the openings in all of said collars and placed over said hats, whereby

number of hats may have their crowns inserted in the remaining collars and be out of contact with the hats first inserted, and a second partition inserted in said receptacle and having collars alining with those in the first partition, and having hats secured therein in the same manner as above described.

5. A crate for packing hats comprising a receptacle, a partition having a number of collars secured therein inserted in the receptacle, and adapted to receive a number of hats having their crowns inserted within certain of said collars, a sheet of material having holes alining with the openings in all of said collars 15 and placed over said hats, whereby a number of hats may have their crowns inserted in the remaining collars and be out of contact with the hats first inserted, a sheet of material having holes alining with the openings of all of 20 said collars placed over said last-named hats, and a series of partitions having collars alining with those in the first partition and superposed thereon, and having hats secured therein in the same manner as above described.

25 6. Apparatus for packing hats comprising a partition having a number of collars secured therein and projecting above and below the partition, certain of said collars projecting a greater distance above the partition than others, and a sheet of suitable material, as paper, provided with openings equal in number to and adapted to aline with the openings in said 30 collars.

7. Apparatus for packing hats comprising a partition having a number of collars secured 35 therein and projecting above and below the partition, a second partition having a like number of collars secured therein in a similar manner, but being of a less depth than said first-named collars, and a number of sheets of a 40 suitable material, as paper, provided with openings equal in number to, and adapted to aline with the openings in, the collars of said partitions.

8. Apparatus for packing hats comprising 45 a partition having a number of collars secured therein and projecting above and below the partition, certain of said collars projecting a greater distance above the partition than others, a plurality of partitions having a like number 50 of collars secured therein in a similar manner but being of a less depth than said first-named collars, certain of said collars projecting a greater distance above said partitions than the others, and a number of sheets of suitable material, as paper, provided with openings 55 equal in number to and adapted to aline with the openings in, the collars of all of said partitions.

In testimony whereof I have hereunto set 60 my hand in presence of two subscribing witnesses.
